UNITED STATES PATENT OFFICE

105,093

DESIGN FOR AN OIL BURNER

Christopher L. Fontana, Cedar Rapids, Iowa, and Arthur C. Haggstrom, Rockford, Ill., assignors to Autocrat Oil Burner Corporation,
Cedar Rapids, Iowa, a corporation of Iowa

Application April 26, 1937, Serial No. 68,987

Term of patent 7 years

To all whom it may concern:

Be it known that we, Christopher L. Fontana, a citizen of the United States, residing at Cedar Rapids, in the county of Linn and State of Iowa, and Arthur Chas. Haggstrom, a citizen of the United States, residing at Rockford, in the county of Winnebago, State of Illinois, have invented a new, original, and ornamental Design for Oil Burners, of which the following is a specification, reference being had to the accompanying drawings forming part thereof.

We claim:

The ornamental design for an oil burner as shown, and described.

CHRISTOPHER L. FONTANA.
ARTHUR CHAS. HAGGSTROM.
